CLAIM

We claim the ornamental design for a concrete screed, as shown and described.

DESCRIPTION

FIG. 1 is a front perspective view of a concrete screed in accordance with an embodiment of the present invention. FIG. 2 is a front view of the concrete screed of FIG. 1.

FIG. 3 is a rear view of the concrete screed of FIG. 1.

FIG. 4 is a left side view of the concrete screed of FIG. 1.

FIG. 5 is a right side view of the concrete screed of FIG. 1.

FIG. 6 is a top view of the concrete screed of FIG. 1.

FIG. 7 is a bottom view of the concrete screed of FIG. 1.

FIG. 8 is a front perspective view of a concrete screed in accordance with another embodiment of the present invention.

FIG. 9 is a front view of the concrete screed of FIG. 8.

FIG. 10 is a rear view of the concrete screed of FIG. 8.

FIG. 11 is a left side view of the concrete screed of FIG. 8.

FIG. 12 is a right side view of the concrete screed of FIG. 8.

FIG. 13 is a top view of the concrete screed of FIG. 8; and,

FIG. 14 is a bottom view of the concrete screed of FIG. 8.

The portions of the concrete screed shown in broken lines are included for the purpose of illustrating environment and form no part of the claimed design.
